UNITED STATES PATENT OFFICE.

GEORGE P. GUERIN, OF CHICAGO, ILLINOIS.

DESIGN FOR A GAME-BOARD.

43,874.

Specification for Design.

Patented Apr. 22, 1913.

Application filed December 26, 1912. Serial No. 738,749. Term of patent 14 years.

To all whom it may concern:

Be it known that I, GEORGE P. GUERIN, a citizen of the United States, residing at Chicago, in the county of Cook and State of Illinois, have invented a new, original, and ornamental Design for a Game-Board, of which the following is a specification, reference being had to the accompanying drawing, forming part thereof.

The figure is a plan view looking down upon the game board.

I claim:

The ornamental design for game board, as shown.

GEORGE P. GUERIN.

Witnesses:

EPHRAIM BANNING,

THOMAS A. BANNING, Jr.
